UNITED STATES PATENT OFFICE

BENGT F. FRIBERG, OF ST. LOUIS, MISSOURI, ASSIGNOR TO LACLEDE STEEL COMPANY,
OF ST. LOUIS, MISSOURI, A CORPORATION OF MISSOURI

JOINT FOR CONCRETE SLABS

Application filed November 12, 1929. Serial No. 406,652.

This invention relates generally to joints for concrete slabs of the type disclosed in an application bearing Serial No. 355,055, filed by me on April 15, 1929, and particularly to a joint of this character provided with improved means for receiving the stakes employed to secure the joint in upright position prior to and during the operation of pouring the concrete thereabout.

10 My invention also relates to a joint of the character described which is provided with improved means for connecting adjacent sections of said joint together, the predominant object of this feature of the invention being to produce an improved joint of this type which is so constructed and arranged that an element on each section of the joint interlocks with a portion of an adjacent section of the joint to provide a continuous joint.

15 Another important feature of the invention is to provide a joint of the type referred to above with interlocking elements for connecting adjoining sections of the joint together, which are so constructed and arranged as to receive the stakes by which the joint is maintained in an upright position prior to and during the operation of pouring the concrete thereabout and during the setting of said concrete.

20 Fig. 1 is a fragmentary side elevation of a joint constructed and arranged in accordance with the present invention.

Fig. 2 is a side elevation of a portion of the joint illustrated in Fig. 1 drawn on an enlarged scale.

25 Fig. 3 is a fragmentary horizontal section on line 3—3 of Fig. 2.

Fig. 4 is a vertical section on line 4—4 of Fig. 2.

30 Fig. 5 is a view similar to Fig. 3, but showing another manner of locking a pair of joint sections together.

In the drawings, wherein is shown for the purpose of illustration, merely, one embodiment of the invention, A designates my improved joint which may comprise a pair of strip portions spaced apart in a vertical direction; there being in the drawings an upper strip portion 1 and a lower strip portion 2, each of which extends longitudinally of

the joint A. 3 designates a space between the strip portions 1 and 2, and extended transversely of the space 3 are connecting portions 4 which are spaced longitudinally of the joint and which serve to connect the strip portions 1 and 2 together.

The joint A is comprised of a plurality of joint sections as shown in Figs. 1 and 2, and located at an end of each of said joint sections is an interlocking element 10, said interlocking element preferably being formed integral with the joint section with which it is associated by being stamped therefrom, and being curved when viewed in plan to provide a semicircular catch, as shown most clearly in Fig. 3. Each interlocking element 10 is provided with a raised strengthening bead 11 which follows the curved outer face of said interlocking element, whereby said interlocking elements are provided with sufficient strength to withstand the usage to which they are subjected without said elements being bent or broken.

At the end of each section of the joint A same is provided with an aperture 12 through which the interlocking element 10 of the adjacent joint section extends, as illustrated in Fig. 3, and by so extending the interlocking elements of the joint sections through the apertures 12 of adjacent joint sections, said adjoining joint sections are connected together so they may not move longitudinally with respect to each other, whereby a continuous joint is provided.

13 designates stakes which serve to maintain the joint A in its proper vertical position prior to and during the operation of pouring concrete about the joint and during the setting of said concrete. The stakes are preferably stamped from sheet metal, and, as shown clearly in Fig. 3, are semicircular in cross-section, and each of said stakes is provided with a tapered lower portion to facilitate the operation of driving said stake in the ground. Also in forming said stakes each thereof is provided with a substantially U-shaped slit, and the material within said slit is displaced in an outward direction to provide the stake with a lip 14, which serves as a stop to limit the downward movement of

the stake with respect to the joint A, and thereafter to prevent any vertical displacement of the joint.

In setting up my improved joint preparation to incorporating same in a roadway, the interlocking elements 10 of the respective sections of the joint are passed through the apertures 12 of adjoining sections, in the manner illustrated in Fig. 3. The stakes 13 10 are then passed downwardly through the semicircular interlocking elements; that is to say, each stake will be extended between the inner face of the interlocking element with which it is associated, and the adjacent face 15 of the joint section connected to the joint section on which said interlocking element is formed. The stake is then driven into the ground, and the stakes will support the joint in its proper vertical position and will prevent separation of the joined joint elements 20 in a direction transversely with respect to said joint sections. The lips 14 on the stakes 13 prevent the stakes from being driven too far downwardly with respect to the joint, said 25 lips being so arranged that they will contact with the top edges of the associated interlocking elements 10, whereby such downward movement of the stakes will be arrested, and thereafter any vertical displacement of the 30 joint prevented.

Each of the joint sections is provided with an interlocking element 10 at one end thereof, and an aperture 12 at its opposite end, and intermediate of its ends each of said 35 joint sections is provided with a plurality of elements which are constructed and arranged just as are the interlocking elements 10. The latter elements, which are designated by the reference character 15 in the drawings, 40 are merely stake-receiving elements and serve no purpose other than to provide pockets through which stakes 16 are driven, hence said stakes 16 serve the sole purpose of aiding in supporting the joint in its proper vertical position, and when provided with the lips 14 said stakes prevent displacement of the joint in a vertical direction.

In Fig. 5 I illustrate another manner of locking a pair of joint sections together. In 50 accordance with this arrangement the interlocking element 10 on one joint element is passed through the aperture 12 on an adjoining section, after which the joint section provided with the aperture is moved longitudinally with respect to the joint section 55 provided with the interlocking element so as to cause the portion 12' of the section provided with the aperture to move into the interlocking element 10 on the adjoining section. By 60 this arrangement a very secure joint is obtained when the associated stake 13 is passed through the interlocking element.

The stake-receiving elements 15 and the interlocking elements 10 are connected to the 65 joint sections at one side only of each of said

stake-embracing elements and are formed of material possessed of sufficient resiliency so that when the stakes 16 and 13 are driven through the elements, said elements will be expanded slightly. In view of this arrangement the resilient elements referred to will grip the stakes and force them tightly against the adjacent faces of the joint, whereby close contact will be obtained between the stakes and the joint sections. 75

I claim:

1. A joint for roadways comprising a plurality of joint sections, and means for securing said joint sections together to provide a continuous joint structure, said means comprising an interlocking element on one of said joint sections adapted to be extended through an aperture formed in an adjoining joint section, and means comprising a stake extended through said interlocking element for preventing accidental disengagement of the joint sections and supporting the joint in an upright position prior to the completion of the roadway. 80

2. A joint for roadways comprising a plurality of joint sections, and means for securing said joint sections together to provide a continuous joint structure, said means comprising a substantially U-shaped interlocking element on one of said joint sections adapted to be extended through an aperture formed in an adjoining joint section, and means comprising a stake extended through said U-shaped interlocking element for preventing accidental disengagement of the joint sections and supporting the joint in an upright position prior to the completion of the roadway, said U-shaped interlocking element being connected at one of its sides only to the associated joint section and being formed of resilient material whereby same is rendered yieldable so as to grip the stake extended therethrough. 90

3. A joint for roadways comprising a plurality of joint sections, means for securing said joint sections together to provide a continuous joint structure, said means comprising a substantially U-shaped interlocking element on one of said joint sections adapted to be extended through an aperture formed in an adjoining joint section, and means extended through said interlocking element for preventing accidental disengagement of the connected joint sections, the last-mentioned means comprising a stake which aids in supporting the joint in an upright position prior to completion of the roadway. 100

4. A joint for roadways comprising a plurality of joint sections, means for securing said joint sections together to provide a continuous joint structure, said means comprising a substantially U-shaped interlocking element on one of said joint sections adapted to be extended through an aperture formed in an adjoining joint section, and means ex- 115 120 125 130

tended through said interlocking element for preventing accidental disengagement of the connected joint sections, the last-mentioned means comprising a stake which aids in supporting the joint in an upright position prior to completion of the roadway, said interlocking element being formed of resilient material so as to cause same to grip the stake driven therethrough.

10 5. A joint for roadways comprising a plurality of joint sections, and means for securing said joint sections together to provide a continuous joint structure, said means comprising a yieldable interlocking element on one of said joint sections adapted to be extended through an aperture formed in an adjoining joint section, and means comprising a stake extended through and gripped by said interlocking element for preventing 15 accidental disengagement of the joint sections and supporting the joint in an upright position prior to completion of the roadway.

20 In testimony that I claim the foregoing I hereunto affix my signature.
